STAND FOR DRESS FORMS AND THE LIKE

Daniel H. Chason, Elizabeth, N. J., assignor to
The Singer Manufacturing Company, Elizabeth,
N. J., a corporation of New Jersey

Application September 16, 1942, Serial No. 458,501

7 Claims. (Cl. 223—120)

This invention relates to stands for supporting dress-forms and the like and more particularly for supporting dress-forms comprising hollow shells molded to conform to the contours of human models.

The invention has for its primary object to provide an improved stand of this nature in which the upper portion of the stand and the dress-form supported thereby are adjustable vertically relative to the base of the stand and are normally locked against rotation relative thereto.

Another object of the invention is to provide conveniently actuated treadle-controlled means for unlocking the upper portion of the stand from its base portion to permit the upper portion and the dress-form carried thereby to be turned freely about a vertical axis while fitting a dress thereto.

Another object of the invention is so to construct the treadle-controlled locking means that it will also serve normally to lock the upper portion of the stand and its base portion against axial separation but which, when released, will permit the upper portion of the stand to be removed from the base portion to facilitate packing, storage, etc.

Still another object of the invention is to provide, in a stand of this nature, an improved tapered dress-form-supporting neck-section which is manually adjustable as to size and readily deformable as to contour, thereby to permit the neck-section to adapt itself to irregular neck shapes.

A further object is to provide improved and simplified adjustable means for yieldingly supporting the lower portion of the dress-form against lateral movement relative to the stand.

These and other objects have been attained by the provision of a stand as disclosed in the accompanying drawing illustrating a preferred embodiment of the invention.

In the drawing,

Fig. 1 is a side elevation of the improved stand, showing, in dotted lines, a dress-form supported thereon.

Fig. 2 is an enlarged fragmentary elevation of the improved stand with certain parts broken away and other parts shown in section, more fully to disclose the structural characteristics of the stand.

Fig. 3 is a transverse section taken on the line 3—3 of Fig. 2.

Fig. 4 is an enlarged detail sectional view of the means for locking the upper and lower sections

of the stand together against axial separation and relative rotation.

Fig. 5 is an enlarged bottom view of the free end of one of the four arms which yieldingly hold the lower end of the dress-form against lateral movement.

Fig. 6 is a plan view of the form-supporting neck-section of the improved stand, showing, in dotted lines, the neck-section deformed.

Referring more specifically to the drawing, the invention is disclosed as embodied in a stand comprising a base-frame B, an upright standard S, supported by said base-frame, a form-supporting neck-frame N secured upon the upper end 10 of the standard and a vertically and horizontally adjustable dress-form skirt-support D secured upon the standard and adapted yieldingly to engage the inner surface of the skirt portion of the dress-form F to hold the latter against substantial lateral movement.

The base-frame comprises three equally spaced flat-metal legs 1, 2 and 3 each of which has two upwardly inclined portions a and b secured, respectively, to header plates 4 and 5 secured upon 15 a vertically arranged tube 6 constituting one element of the standard S. Intermediate the portions a and b each leg is formed with a foot-portion c adapted to rest upon the floor.

The standard S comprises the tube 6, supported 20 in vertical position by the base B and clamped thereto by a wing-nut t threaded on a stud v secured within the lower end of the tube, and a rod 7 telescopically fitted within the tube. At its upper end the rod 7 is reduced in diameter to

afford a supporting shoulder for a cross-head 8 on the down-turned ends 8^a of which the neck-frame N is pivotally mounted as by pivot pins 9. A wing-nut n threaded on the reduced upper end of the rod 7 clamps the cross-head 8 thereon.

40 The neck-frame, which is adapted to fit within the neck portion of the dress form to support the weight thereof, is of truncated conical form and comprises two semi-conical thin sheet metal members 10 and 11 pivotally mounted at their upper ends on the pivot pins 9. At their lower ends the members 10 and 11 are slidably fitted within each other for circumferential adjustment to adapt the neck-frame to dress-form necks of various sizes. Clamp screws 12, carried by one member and passing through arcuate slots 13 in the other member, are fitted with clamp nuts 14 for clamping the members 10 and 11 in adjusted positions. In Fig. 2 the members 10 and 11 are shown in full lines as adjusted for a dress-form 45 having one size neck section and, in dotted lines,

as adjusted for a dress-form having a smaller neck section.

In the drawing the thickness of the metal of the members 10 and 11 has been shown greatly exaggerated. In practice the metal is sufficiently thin and flexible as to permit the neck-frame to be readily deformed by the weight of the dress-form, as indicated in dotted lines in Fig. 6 to permit it to adapt itself to various neck shapes. This insures surface contact between the neck-frame and the neck section of the dress-form as distinguished from line or point contact.

The support D which is located within and engages the lower end of the dress-form F to hold it against substantial lateral movement comprises a split sleeve 15 slidably mounted on the rod 7 and adapted to be contracted to grip the rod by a clamp screw 16. Secured upon the upper end of the sleeve 15 are transverse cross-bars 17 having adjustably mounted thereon extension arms 18. These arms are adapted to be secured in adjusted positions on the bars 17 by bolts 19, carried by the arms and projecting through slots 20 in the bars, and clamp nuts 21 threaded on said bolts. At their outer ends the extension arms carry dress-form engaging elements comprising resilient bow-spring fingers 22 adapted, by endwise adjustment of the bars 18, to be brought into contact with the inner face of the dress-form supported on the neck-frame N. These fingers 22, being resilient, will readily adapt themselves to the inner contours of individual dress-forms.

To prevent the dress-form from having uncontrolled rotation relative to the base B means is provided for normally locking the rod 7 against rotation in the tube 6. It is desirable, however, to be able to turn the dress-form about a vertical axis while fitting a dress thereto and therefore means, actuatable at will, has been provided for rendering said locking means temporarily ineffective. This locking means comprises a disk 23 carried by a split sleeve 24 clamped upon the rod 7 by a pinch-screw 25. The periphery of the disk is serrated, thereby affording a series of teeth 26 with spaces 27 therebetween. Clamped on the upper end of the tube 6 by a clamp-bolt 28 is a second split sleeve 29 having an off-set wing portion 30 within which is pivotally mounted, on bolt 28, a latch-lever 31 having an edge portion 31a adapted normally to fit within one of the spaces 27 between the teeth 26 to prevent rotation of the rod 7 and the dress-form carried thereby. The latch-lever 31 is normally urged in a counter-clockwise direction, as viewed in Figs. 2 and 4, to cause its upper end to enter one of the spaces 27, by the upward pressure of a spring-pressed rod 32 slidably mounted in apertures 4a-5a in the header-plates 4 and 5, respectively, and having its upper end pivotally connected to the off-set portion 31b of the latch lever. A coil spring 33, surrounding the rod 32 and interposed between the header-plate 4 and an abutment 34 carried by the rod, normally urges the rod upwardly to cause the latch 31 to engage between the teeth of the disk 23.

At its lower end the rod 32 is formed as a treadle 35 upon which the user may step to depress the rod 32 and retract the portion 31a of the latch 31 from between the teeth 26 of the disk 23, thereby to permit rotation of the rod 7 and the dress-form carried thereby.

The weight of the rod 7 and the parts carried

thereby is normally transmitted to the upper end of the tube 6 by the disk 23. To prevent accidental separation of the rod 7 from the tube 6 the latch-lever 31 is formed with a projecting finger 31c which normally overlies the solid portion of the disk 23 and thereby locks the disk to the sleeve 29 fixed upon the upper end of the tube 6. When it is desired to disassemble the stand as, for example, for storage purposes, the treadle 35 is depressed and the latch-lever 31 is tipped to the position shown in dotted lines in Fig. 2, in which position the rod 7 and disk 23 secured thereto may be raised relative to the tube 6, the finger 31c of the latch passing through a space 27 between two teeth 26 of the disk.

Having thus set forth the nature of the invention, what I claim herein is:

1. In a stand for dress-forms and the like comprising a base, a standard including an upright tube secured to said base and a rod rotatable and axially movable in said tube and dress-form supporting means carried by said rod, the improvement which consists in the provision of a serrated disk secured upon said rod, a latch-lever carried by said tube and having one portion normally engaging one of the serrations of said disk to prevent rotation of the disk and the rod on which it is secured relative to said tube and another portion overlying said disk to prevent axial separation of said tube and rod, and treadle-controlled means for releasing said latch.

2. In a stand for dress-forms and the like comprising a base, a standard including an upright tube secured to said base and a rod rotatable and axially movable in said tube, and dress-form supporting means carried by said rod, the improvement which consists in the provision of a sleeve clamped to said rod and resting upon the upper end of said tube to support the weight of said rod thereon, a serrated disk carried by said sleeve, a second sleeve secured upon the upper end of said tube, a spring-pressed latch-lever carried by said second sleeve and having one portion normally engaging said disk to prevent rotation thereof relative to said tube and another portion normally overlying said disk to prevent axial movement thereof relative to said tube, and treadle-actuated means to retract said latch-lever thereby to release said disk to permit rotation and axial movement of said disk and rod relative to said tube.

3. In a stand for dress-forms and the like comprising a base and a standard rising vertically from said base, the improvement which consists in the provision of a neck-frame carried by the upper end of said standard and comprising a cross-head secured upon said standard, a split truncated conical member pivotally mounted on said cross-head and constructed and arranged to fit within and support the neck portion of a dress-form, and means to vary the size and taper of said member to conform to the neck-size of a specific dress-form to be placed thereon.

4. In a stand for dress-forms and the like comprising a base and a standard rising vertically from said base, the improvement which consists in the provision of an adjustable neck-frame carried by the upper end of said standard and comprising a cross-head secured upon said standard and two truncated semi-conical members pivotally mounted adjacent their upper ends on said cross-head and having their lower ends arranged in overlapping relation with each other, and clamping means carried by the overlapped

portions of said members for locking the members together in various adjusted positions.

5. A stand for dress-forms and the like comprising a base, a vertically disposed standard rising from said base, a neck-frame secured upon the upper end of the standard and adapted to support a dress-form pendent therefrom, a plurality of transversely arranged cross-bars mounted upon said standard, an extension arm adjustably mounted on each end of each cross bar and a pair of bow-spring fingers carried by each of said extension arms and adapted to engage the inner surface of a dress-form depending from said neck-frame.

6. In a stand for dress-forms having a base, a standard rising vertically from said base and press-form supporting means carried by said standard, the improvement which consists in the provision of an adjustable and deformable neck-frame pivotally secured upon the upper end of said standard and comprising a truncated conical member including a plurality of sections ad-

justably secured together and made of readily deformable material constructed and arranged to fit within and support the neck portion of a dress-form and to conform to irregular neck shapes under the weight of a dress-form suspended thereon.

7. In a stand for dress-forms having a base and a standard rising vertically from said base, the improvement which consists in the provision 10 of a truncated conical neck-frame pivotally secured upon the upper end of said standard, said neck-frame being adjustable as to size and taper and deformable as to contour to adapt it to fit within and support the neck portions of dress forms of various sizes and shapes, said neck-frame comprising a plurality of tapered shell sections of relatively thin sheet material pivoted together adjacent their upper ends and means adjustably securing together the complementary 15 marginal portions of the lower ends of said sections.
